UNITED STATES PATENT OFFICE

O. L. HOPSON, OF WATERBURY, AND H. P. BROOKS, OF WOLCOTTVILLE,
ASSIGNORS TO THE TURNER & CLARK MANUFACTURING COMPANY, OF
WOLCOTTVILLE, CONNECTICUT.

IMPROVEMENT IN BUCKLES.

Specification forming part of Letters Patent No. 58,725, dated October 9, 1866.

To all whom it may concern:

Be it known that we, ORIN L. HOPSON, of Waterbury, in the county of New Haven and State of Connecticut, and HEMAN P. BROOKS, of Wolcottville, in the county of Litchfield and State of Connecticut, have invented, made, and applied to use a certain new and useful Improvement in Buckles; and we do hereby declare the following to be a full, clear, and exact description of the same, reference being had to the annexed drawings, making part of this specification, wherein—

Figure 1 represents the frame of the buckle. Fig. 2 is a view of the buckle complete, and Fig. 3 is a perspective view of the wire tongue separately.

Similar marks of reference denote the same parts.

The frames of buckles have heretofore been made of wire bent to the proper shape and then flattened at certain portions by means of dies.

The nature of our said invention consists in a buckle-frame formed with a double bend in each side between the main portion of the frame and the loop, and which bend forms the bar or axis for the tongue to swing upon, and we combine therewith a tongue formed of wire with eyes around the said axis in the double bend of the frame.

In the drawings, *a* is the main portion of the buckle-frame, and *b* is the loop forming the part for the attachment of the strap. These are made of one piece of wire, bent into

the shape shown in Fig. 1, with the double bends in each side, and the frame is stiffened by being flattened at portions, such as the top of the main part *a*.

At the parts *c c* in the double bends of the frame the wire is to be left round, so as to form the axis or bar for the tongue *d*. The tongue *d* is to be properly shaped so as to be attached at the parts *c c* of the frame, and we prefer and use a wire tongue, such as shown in Fig. 3, wherein the eyes *e e* are bent up to set around the axis *c c*, and said eyes are connected by the wire extending from one to the other, as at *i*.

What we claim, and desire to secure by Letters Patent, is—

1. The buckle-frame formed with double bends in the sides between the main portion and the loop, one portion of said double bend at each side of the frame, forming the axis for the tongue, substantially as specified.

2. The wire tongue formed with eyes connected by the central portion of the wire, in combination with the aforesaid buckle-frame having double bends in its sides, substantially as set forth.

In witness whereof we have hereunto set our signatures this 23d day of April, A. D. 1866.

ORIN L. HOPSON.
HEMAN P. BROOKS.
